TELEVISION SYSTEM AND SYNCHRONIZING
MEANS THEREFORRichard L. Campbell, Hasbrouck Heights, N. J.,
assignor to Allen B. Du Mont Laboratories, Inc.,
Passaic, N. J., a corporation of Delaware

Application October 19, 1939, Serial No. 300,263

13 Claims. (CL 178—6.8)

My invention relates to improvements in television systems and synchronizing means therefor.

By using interlaced scanning in television communication with cathode-ray tubes, important advantages are obtained. However, in the various systems and methods proposed heretofore to synchronize for interlaced scanning with even the lowest interlace ratio of two, it has been found that positive interlace action at the receiver is difficult to maintain, although operating conditions might be made as ideal as possible. In order to obtain any degree of satisfactory results to maintain positive interlace action at the receiver, use of a rather complicated pulse form for the vertical synchronizing wave, which has both low and high frequency components, has been resorted to heretofore. Since the frequency content of the horizontal and vertical waves overlap in this system and method of the prior art, they cannot be effectively separated at the receiver, with the result that the desired, positive interlace action is not always maintained. Furthermore, in the prior systems and methods, the complex synchronizing wave forms embraced such expedients as equalizing pulses, serrated waves, and interrupted horizontal pulses. Also, the quality of the synchronizing pulses after separation was not as good as desired, the vertical synchronizing was affected by low frequency video transients and low-frequency surges, and there was serious distortion of the horizontal synchronizing wave train during occurrence of the vertical synchronizing pulses.

With the foregoing in mind, it is one of the objects of my invention to provide an improved television system and synchronizing means therefor, whereby substantially more adequate separation of vertical and horizontal synchronizing signals is attained than is possible with the various systems and methods used heretofore, and to provide a means of continuous transmission of horizontal synchronizing signals without impairing the effectiveness of vertical synchronizing.

Another object of my invention is the provision of an improved television system and synchronizing means therefor, which not only gives more satisfactory synchronizing performance at the receiver, but which also makes possible generation of vertical synchronizing signal at the transmitter by means substantially simpler than the means used heretofore, for interlaced scanning.

Another object of my invention is the provision of an improved television system and synchronizing means therefor, in which there is used a vertical synchronizing signal whose frequency content is such that it can be substantially entirely removed from the horizontal signal without detrimental effect on the horizontal synchronizing, so that the vertical synchronizing does not interfere with horizontal synchronizing operation of the receiver.

Another object of my invention is the provision of an improved television system and synchronizing means therefor, in which a vertical synchronizing pulse is transmitted in such a way that it can be readily separated from the combined video and synchronizing signals and in a manner so effective that the separated horizontal and vertical pulses at the receiver are so pure that they can drive the respective sweep circuits at the receiver more effectively than in the systems and methods used heretofore, thereby giving exceedingly positive synchronization.

Another object of my invention is the provision of an improved television system and synchronizing means therefor, in which the horizontal and vertical synchronizing pulses can be separated so well and effectively that no frequency adjustment is necessary at the receiver, whereby the receiver will follow the transmitter over a considerable range which is not feasible in circuits using the old type of synchronizing pulses referred to.

Another object of my invention is the provision of an improved television system and synchronizing means therefor, in which both horizontal and vertical synchronization are so positive and effective that simplification of receiver controls is possible to the extent that the synchronizing controls heretofore necessary at the receiver can be eliminated.

Another object of my invention is the provision of an improved television system and synchronizing means therefor, in which it is possible to use at the receiver aperiodic sweep circuits which can be made to synchronize automatically over a wide range of scanning frequencies, whereby the receiver will respond to a television transmitting system which is flexible in the sense that the respective frequencies of the pulses transmitted for horizontal and vertical synchronization might be changed as occasion or requirements might arise.

Other objects and advantages will hereinafter appear.

53 In accordance with my invention, pulses of a

high, radio-frequency wave are used for vertical synchronizing. This wave, which may have an approximate frequency of 529 k. c., for example, is electronically keyed during the intervals for vertical synchronizing, and these pulses are mixed with the horizontal synchronizing signals and transmitted along with the video signals in much the same manner as commonly used in the present television systems. At the receiver, the pulses of the radio-frequency wave for vertical synchronizing are separated out by employing a tuned stage, responsive to the frequency of this wave, to select the vertical synchronizing signals or pulses which are then applied to the vertical synchronizing circuit. The video and horizontal synchronizing components in the received composite signal are thus effectively excluded from the vertical synchronizing circuit. The pulses of the wave at radio-frequency, for vertical synchronizing, are removed from the signals applied to the horizontal synchronizing circuit by means of a wave trap, so that only the horizontal synchronizing signals are applied to the horizontal synchronizing circuit.

My invention resides in the improved system and method of the character hereinafter described and claimed.

For the purpose of illustrating my invention, an embodiment thereof is shown in the drawings, wherein

Figure 1 is a simplified, diagrammatic view of a television transmitting system constructed and operating in accordance with my invention;

Fig. 1a is a graphical view illustrative of the principle of operation in Fig. 1;

Fig. 2 is a simplified diagrammatic view of a television receiving system for intercepting and using the signals transmitted from a system such as is shown in Fig. 1;

Fig. 3 is a view similar to Fig. 1, showing a modification; and

Figs. 4, 4a and 5 are graphical views illustrative of the principle of operation in Fig. 3.

With reference to Fig. 1, there is employed a synchronizing generator 10 which is of the usual, conventional construction, with the exception of omission of the complicated circuit used heretofore to form the complex synchronizing wave forms of the prior art systems and methods referred to.

The carrier source 11 for the vertical synchronizing pulses or signals, represented at 12 in Fig. 1a, comprises a frequency multiplier, which is driven from the master oscillator of the frequency divider in the synchronizing generator 10, and which provides a 529.2 k. c. wave, represented at 13, which is synchronous with the horizontal synchronizing pulses supplied from the generator 10 at the rate of 13,230 per second, as represented at 14. A constant phase relation is therefore maintained between the wave 13 for vertical synchronizing and the horizontal synchronizing pulses 14.

The carrier 13 is fed to a tuned amplifier 15 which is modulated by pulses, represented at 16 and supplied from the synchronizing generator 10, and which occur at the desired vertical scanning frequency of 60. The output of the amplifier 15, represented at 17, is therefore a series of the vertical synchronizing pulses 12, taken from the radio-frequency wave 13, and these vertical synchronizing pulses or signals 12 occur at the desired vertical pulse or field frequency of 60.

By means of the mixing amplifier shown, and designated generally by the reference numeral

18, the output signal 17 from the amplifier tube 15 is mixed with the horizontal synchronizing pulses 14, to obtain in the output line 19 the composite synchronizing signal represented in Fig. 1a. In the radio transmitter 20, this composite signal is mixed in the well known manner with the video signals from the amplifier 21, to form a composite television signal. In the transmitter, that part of the vertical synchronizing pulses, represented by the lighter portions 22 in Fig. 1a, is "clipped" or "saturated off" in the well known manner.

From the foregoing it will be seen that in my improved system and method, the horizontal synchronizing pulses or signals 14 are not interrupted to permit insertion of the vertical synchronizing pulses 12, as in the various systems proposed heretofore, but are allowed to and actually do remain on continuously. Therefore, the pulses 14 at the horizontal scanning frequency of 13,230, are simply obtained from the frequency divider unit of the synchronizing generator 10, and mixed with the vertical synchronizing pulses 12 without requiring a "blanking" amplifier for insertion of the vertical pulses, as heretofore.

In my improved system and method, it is to be noted that the carrier 13 is applied to the grid of tube 15 which the tube 37 controls by means of the common cathode connection shown. The control tube 37 is adjusted to draw sufficient plate current so that tube 15 is biased off at times or intervals when there is no signal on the grid of the tube 37. When the vertical signals 16 are applied to the grid of tube 37 in negative polarity, the current in the common cathode resistor 38 decreases to where tube 15 becomes operative to allow a pulse of carrier frequency to appear in the plate transformer 39 of tube 15, from whence it is applied to the grid of tube 35 for mixing with the horizontal synchronizing pulses 14 from the tube 36.

The tubes 35 and 36 are mixer tubes, of the vertical and horizontal synchronizing pulses 12 and 14, respectively. There is a continuous train of the horizontal synchronizing pulses 14 applied to tube 36, and these pulses are mixed with the vertical carrier pulses 12 in this form, in the common resistor 40, from whence these mixed pulses are applied to the grid of tube 41 which may be a cathode load stage for low impedance output. The mixed synchronizing pulses or composite synchronizing signal, shown in Fig. 1a, is fed by line 19 from tube 41 to the transmitter 20, where it is superimposed on or added to the video signal, as explained.

The basic composite synchronizing signal as represented in Fig. 1a, is comprised of a continuous train of the horizontal pulses 14 and the pulses 12 of the radio-frequency wave 13.

The negative half-cycles of the vertical synchronizing pulses 12 extend considerably below the axis, as shown in Fig. 1a. These negative half-cycles also extend considerably below the negative portion of the horizontal pulses. The equal positive and negative portions of the carrier are not the best type of synchronizing signal, because the negative loop of the carrier is visible on the received picture. Therefore, it might be desirable to "clip off" this negative loop and obtain a resulting signal such as is shown in Figs. 4 and 4a.

For the above purpose, there may be used a circuit such as is shown in Fig. 3, in which parts 75 which correspond to and serve the same purpose

as those in Fig. 1 have been designated by the same respective reference numerals as the latter. The tube 42 is operated as a "clipping" or distorting stage so that the lower nodes of vertical pulse extending below the axis as shown in Fig. 1a, are removed. This is accomplished by over-biasing tube 42 with a low applied screen voltage and operating so that only the positive peaks of the wave are effective.

The tube 43 is for the purpose of removing the added components in the region of the vertical pulse, and they are removed in this stage in a manner similar to the manner of operation of tube 42. The output of tube 43 is applied to the grid of tube 41, and the output synchronizing wave in line 19 is as shown in Figs. 4 and 4a. On account of the relation of scanning frequencies chosen, there will be interlaced scanning, with an interlace ratio of two. Fig. 4 represents the composite synchronizing wave for the odd frames, for example, while Fig. 4a represents the composite synchronizing wave for the even frames.

As illustrated more clearly in Fig. 5, the vertical synchronizing wave resulting from the operating action in Fig. 3 is no longer a radio-frequency carrier pulse, but is a series of positive half cycles of radio frequency, which introduces new frequency components in the synchronizing wave.

The carrier wave before "clipping" by the tube 42 is of sinusoidal form, at the selected frequency of 529.2 k. c. After "clipping" by the tube 42, the synchronizing signal is comprised of positive half-sine loops, occurring at the rate of 529,200 per second. This so-called "clipping" operation is only necessary for preventing the vertical synchronizing pulse from showing up at the receiver.

Aside from the above, it may be desirable to transmit the lower, negative loops, as in Fig. 1, and eliminate them at the receiver.

The chopping off at the transmitter of the lower loop of the carrier wave does not seriously affect the vertical synchronizing performance, but the low frequency component thereby introduced does some harm to the horizontal synchronizing action. Another effect is the introduction of new frequencies, which makes it more difficult at the receiver to remove the vertical synchronizing signal from the horizontal synchronizing signal. In practice, however, my improved system and method works well both ways, although it is more sound theory from the standpoint of separation of the two synchronizing signals, to operate as illustrated in Fig. 1.

At the receiver, shown in Fig. 2, a selective amplifier 44 is connected as represented to the output of the second detector 45 for the purpose of obtaining the vertical synchronizing pulses. This amplifier has band-pass characteristics in the region of 525 k. c. to 535 k. c. In the circuit shown, the selected vertical pulse is applied directly to the grid of a gas-discharge tube 46 which has relatively high mu, and which generates the vertical scanning saw-tooth wave for the vertical sweep circuit 47 connected as shown to the associated deflecting plates.

The horizontal synchronizing signals are passed through a filter 48 to remove the vertical synchronizing signal, and are then applied to the horizontal synchronizing amplifier 49 which removes video components by means of amplitude selection, as will be well understood. The output of the amplifier 49 is therefore a continuous wave

train of the horizontal pulses which are applied to the horizontal sweep circuit 50 at considerable amplitude in order to effect positive synchronization of this circuit. Because the vertical synchronizing signal is removed so effectively, a high amplitude of horizontal pulse can be used without the distortive effects which would take place if vertical synchronizing signals were present in the horizontal signals.

10 In the operation of the vertical sweep circuit 47, the output of the tuned transformer 51 is applied to the grid of the gas-discharge tube 46 so that the incoming pulses of the vertical synchronizing carrier cause this tube to discharge the series-connected condensers 52 and 53. After the discharge, the gas tube 46 becomes non-conductive, and the condensers 52 and 53 are charged through the resistor 54, which furnishes the scanning portion of the saw-tooth wave applied to the output circuit. The gas tube 46 is so operated that it is essentially a non-oscillating device, and requires the grid signal to start conduction.

Due to the fact that the type of vertical synchronizing pulse employed can, in my improved system and method, be very positively and effectively separated from other signals, the synchronizing signal as applied to the grid of tube 46 is sufficiently pure so that the non-oscillating type of sweep circuit can be used, thus providing a more positive synchronizing action than if an oscillator type of sweep circuit were used, as heretofore.

The horizontal sweep circuit 50 also embodies a gas-discharge tube 55, and operates in a manner similar to that of the vertical sweep circuit.

The scanning device at the receiver is represented as being a cathode-ray tube 56 of a conventional construction, and comprises a fluorescent screen 57 which is scanned by a ray 58 of electrons. The electron ray 58 is developed by a gun 59, and by means of the plates shown and the respective, associated sweep circuits 47 and 50, is deflected horizontally at a line frequency of 13,230 and is deflected simultaneously vertically at the field frequency of 60. The video signals, supplied from the amplifier 60, are applied in the usual manner to the control grid of the gun 59.

50 By use of a high frequency carrier for the vertical synchronizing pulse, good separation is possible of both pulses. That is to say, the vertical pulse can be separated out by means of a tuned circuit and applied to the vertical synchronizing circuit with very little interference effect from other signals, such as horizontal synchronizing signals and video signals. Also, the vertical pulse can be removed from the horizontal pulses by means of an effective filter circuit, which then provides a more nearly pure wave-train of horizontal pulses, which are continuous for all practical purposes and are not being interrupted during the vertical pulse intervals.

65 One of the reasons why extremely positive synchronization could not be utilized at the receiver heretofore, was the disturbance caused by the vertical synchronizing pulse in the horizontal circuit, which initiated a low-frequency transient requiring several horizontal line periods for recovery. In my improved system and method, on the other hand, positive synchronization is effected by virtue of the fact that the vertical synchronizing pulse is substantially filtered out of the horizontal synchronizing wave-train so that

a more continuous train of pulses is applied to the horizontal sweep circuit, and therefore no transient such as mentioned above can occur.

From the foregoing it will be seen that in my improved method for synchronizing the respective scanning devices at the transmitting and receiving stations, there are mixed the synchronizing signals 14 occurring continuously at the given line frequency with a wave 13 at a radio frequency and which occurs only during intervals at the given field frequency, to obtain thereby the composite synchronizing signal as illustrated in Fig. 1a. Considering the broader aspect of my invention, this resides in use of the source of synchronizing signals 14 occurring continuously at the given line frequency, use of the wave at radio frequency and which occurs only during field intervals as illustrated at 12 in Fig. 1, and use of suitable means for mixing the synchronizing signals 14 and the intermittently occurring radio wave to obtain the composite synchronizing signal as illustrated in Figs. 1a, 4, 4a and 5.

Considering the broader aspect of my invention further, this resides in a system and method such as that disclosed herein, whereby it is possible to use aperiodic sweep circuits for horizontal and vertical deflection. In such case, the vertical sweep circuit would be responsive to frequencies from 20 cycles to 100 cycles, and the horizontal sweep circuit would be responsive to frequencies from 5000 cycles to 20,000 cycles. An aperiodic sweep circuit, as called for in the claims, is intended to be a sweep circuit which is responsive to control pulses or signals which might vary in frequency over a substantial range i. e., a frequency range, of which the highest frequency is from four to five times the lowest frequency; and which has such a characteristic of frequency-response without requiring synchronization or tuning adjustments.

The feasibility of using aperiodic sweep circuits, as in my improved system and method, results in a very important advantage, which is that the entire system is flexible in the sense that the respective frequencies of the pulses transmitted for horizontal and vertical synchronizing might be changed as occasions or requirements might arise, and the sweep circuits at the receiver would still respond satisfactorily without requiring synchronization or tuning adjustments. If the scanning frequencies are changed in my improved system, it may be necessary to adjust the resistances 54 and 61 to get the proper output sweep amplitudes.

The specific frequencies given and the types of tubes designated in the drawings are by way of example only, and may be changed to suit particular requirements.

A more detailed showing of a television receiving system, for intercepting and using the signals transmitted from a system such as is shown in Fig. 1, is disclosed in my copending application filed December 22, 1939 and bearing Serial No. 310,591.

It will be understood that various modifications, within the conception of those skilled in the art, are possible without departing from the spirit of my invention or the scope of the claims.

I claim as my invention:

1. In the art of television communication between two stations, the steps in the method of holding in synchronism the respective scanning devices at said stations, which consist in generating pulses occurring continuously at a given line frequency and pulses at a given field fre-

quency, said pulses at line frequency lasting longer than the interval between line pulses generating a wave at a frequency that is an integral multiple greater than two of the line frequency,

5 utilizing the pulses at the field frequency to obtain synchronizing pulses of said wave occurring at the same rate and at the same intervals as the pulses at the field frequency, mixing the pulses occurring continuously at the line frequency and the pulses of said wave to obtain a composite synchronizing signal having a component consisting of pulses occurring continuously at the line frequency, and utilizing said composite synchronizing signal for the purpose set forth.

10 2. In the art of television communication between two stations, the steps in the method of holding in synchronism the respective scanning devices at said stations, which consist in generating synchronizing signals at a given line frequency, generating from the same source as said line frequency a signal at a frequency greater than twice said line frequency and which is an even multiple of said line frequency, and using said wave to obtain a source of pulses of said wave for synchronization at a given field frequency said pulses lasting longer than the interval between signals at line frequency.

15 3. An electronic synchronizing system for television communication, comprising a source of synchronizing signals occurring at a given line frequency, a source of signals occurring at a given field frequency, a source of supply of a wave at a frequency greater than twice the line frequency, and means for applying said signals at the field frequency to key said wave to obtain synchronizing pulses of said wave occurring at the field frequency and occurring only during the field periods, said keyed signal lasting longer than the interval between signals at line frequency.

20 4. An electronic synchronizing system for television communication, comprising a source of synchronizing signals occurring at a given line frequency, a source of signals occurring at a given field frequency, a source of supply of a wave at a frequency greater than twice the line frequency, means for applying said signals at the field frequency to key said wave to obtain synchronizing pulses of said wave occurring at the field frequency and occurring only during the field periods, said keyed pulse lasting longer than the interval between signals at line frequency, means for mixing said signals occurring at the line frequency and the pulses of said wave to obtain a composite synchronizing signal, and a transmitter embodying a source of a carrier wave and means for modulating said carrier wave by said composite synchronizing signal.

25 5. In a television transmitting system, a transmitter, a scanning device for generating video signals, means for controlling scanning action of said device, means for supplying the video signals to said transmitter without interruption during the field periods, an electronic source of synchronizing signals occurring at a given line frequency, an electronic source of signals occurring at a given field frequency, a source of supply of a wave at a frequency greater than twice the line frequency, means for applying said signals at the field frequency to key said wave to obtain synchronizing pulses of said wave occurring at the field frequency and only during the field synchronizing period, said pulse lasting longer than the interval between line synchronizing signals, and means for mixing said signals occurring at the

line frequency and the pulses of said wave to obtain a composite synchronizing signal, said transmitter embodying a source of a carrier wave and means for modulating said carrier wave by the video signals and by said composite synchronizing signal.

6. An electronic synchronizing system for television communication, comprising a source of supply of synchronizing signals occurring at a given line frequency, a source of supply of signals at a desired field frequency, a source of supply of a wave at a frequency greater than twice the line frequency, an amplifier having an output resonant circuit responsive only to said third-named frequency and comprising a tube having a grid to which said wave is applied, a control tube for said amplifier tube having a grid and adjusted to draw normally sufficient plate current to bias off said amplifier tube, and means for applying said signals at the field frequency in negative polarity to the grid of said control tube whereby the plate current drawn by said control tube decreases at least to a value whereat said amplifier tube becomes operative to allow a pulse of said wave to appear in said resonant circuit of said amplifier tube.

7. An electronic synchronizing system for television communication, comprising a source of synchronizing signals at line frequency, a source of field synchronizing signals, a source of supply of a wave having a frequency greater than twice said line frequency synchronizing signals, means for modulating said wave to key it in only during pulse intervals of field synchronizing signals in a manner so as to produce a field carrier wave of duration of at least one horizontal line interval, and means for mixing said keyed carrier wave with said synchronizing signals that are at line frequency.

8. An electronic synchronizing system for television communication, comprising a source of synchronizing signals at line frequency, a source of field synchronizing signals, a source of supply of a wave having a frequency greater than twice said line frequency synchronizing signals, means for modulating said wave to key it in only during pulse intervals of field synchronizing signals in a manner so as to produce a field carrier wave of duration of at least one horizontal line interval, means for mixing said keyed carrier wave with said synchronizing signals that are at line frequency and means for clipping off the composite pulses of said mixed signals and wave to a flat level.

9. An electronic synchronizing system for television communication, comprising a source of synchronizing signals at line frequency, a source of field synchronizing signals, a source of supply of a wave having a frequency greater than twice said line frequency synchronizing signals, means for modulating said wave to key it in only during pulse intervals of field synchronizing signals in a manner so as to produce a field carrier wave of

slow rise and duration of at least one horizontal line interval, and means for mixing said keyed carrier wave with said synchronizing signals that are at line frequency.

5 10. In a television transmitting system, apparatus for producing a composite television synchronizing wave form, comprising means for producing uniform horizontal synchronizing pulses recurrent at picture line frequency, means for producing a burst of a high frequency carrier lasting longer than one line period, said carrier being more than twice the frequency of said line frequency, means for integrally relating said horizontal synchronizing pulse frequency and said carrier, and means for mixing said horizontal pulses and said burst of high frequency carrier.

20 11. In a television transmitting system, apparatus for producing a composite television synchronizing wave form, comprising means for producing uniform horizontal synchronizing pulses recurrent at picture line frequency, means for producing vertical synchronizing signals, means for producing a burst of a high frequency carrier lasting longer than one line period, said carrier being more than twice the frequency of said line frequency, means for integrally relating said horizontal synchronizing pulse frequency and said carrier, and means for mixing said horizontal pulses and said burst of high frequency carrier.

25 12. An electronic synchronizing system for television communication, comprising a master signal oscillator, synchronizing signals at line frequency derived from said oscillator, means for deriving from said master oscillator a wave train having a frequency higher than said oscillator, a source of pulses at field frequency, means for electronically keying said wave train by said pulses to provide bursts of said waves having a slow rise to maximum level in a time at least as long as 20% of the interval between signals at line frequency, said bursts lasting longer than the time interval between said synchronizing signals at line frequency, and means for mixing said bursts with said synchronizing signals at line frequency.

30 13. An electronic television transmitting system comprising a transmitter, a scanning device for generating video signals, means for controlling scanning action of said device, a source of synchronizing pulses occurring at a given line frequency, a source of synchronizing pulses occurring at substantially uniformly spaced intervals and at a rate corresponding to the desired field frequency, each of said pulses being comprised of electrical pulsations occurring uniformly and only during the field synchronizing interval and said electrical pulses occurring at a rate greater than twice said line frequency, and means for supplying to said transmitter said signals at the line frequency and said synchronizing pulses at field frequency.

RICHARD L. CAMPBELL.
